CHARLES KELLOGG, OF PHILADELPHIA, PENNSYLVANIA.

Letters Patent No. 87,174, dated February 23, 1869.

IMPROVED CAST-IRON CHORD-CONNECTION FOR BRIDGES.

The Schedule referred to in these Letters Patent and making part of the same

To all whom it may concern:

Be it known that I, CHARLES KELLOGG, of the city and county of Philadelphia, and State of Pennsylvania, have invented a new and improved Cast-Iron Chord-Connection for Bridges; and I do hereby declare that the following is a full and exact description thereof, reference being had to the accompanying drawings, making part of this specification.

My improvement relates to the construction of a cast-iron chord-connection, for uniting sections of wrought-iron-tubular chords, and forming bearings for the vertical posts in an iron truss-bridge; and

It consists—

First, in forming said chord-connection with vertical longitudinal cells, to admit the passage of the diagonal tie-rods through the same, while distributing the metal to the best advantage, to resist both the longitudinal and vertical compressive strains to which it is subjected.

Second, in casting a lug or projection from the top of the block, when used in a "deck"-bridge, and connecting thereto the floor-beams, composed of two **I**-beams, in the manner hereinafter described, whereby the beam performs the triple function of a tie, collar, and supporting-beam.

Figure I is a side elevation of one of my improved connecting-blocks, showing portions of the post, chord-sections, tie-rods, and floor-beam, as arranged in a "deck"-bridge.

Figure II is a central cross-section,

Figure III, a plan, and

Figure IV, a horizontal section thereof.

Like letters refer to like parts in each of the figures.

A is my improved connecting-block;

B B, portions of the sections of the top chord, which it unites;

C, the upper portion of one of the posts;

D, one of the beams arranged for a deck-bridge; and

e f, tie-rods, connecting with the lower chord.

The chord-sections are composed of wrought-iron, and may be of circular form, as shown, or of square or other common form of construction.

The block A is preferably hollow cast, (as shown in Figs. II and IV,) with one or more vertical longitudinal webs or walls, g, for supporting and stiffening the

bases thereof against vertical compression, and the ends against the horizontal compression to which it is subjected.

Bosses h h are cast at the ends and bottom, respectively, of size and form to fit in the ends of the chord-sections and the post, or capital, K, the latter being made separate or not, as preferred.

Suitable holes i are also formed in the top and bottom, at each side, to permit the passage of the tie-rods through the outer spaces of the casting, which rods are secured by nuts j in the usual manner.

For deck-bridges, I form the upper surface of each connection with two longitudinal ledges, l l, on which to support the end of the floor-beam, which can be readily fitted thereto, and with a projection, m, for securing the beam in place.

This beam is composed of two separate beams, the inner edges of the lower flanges o of which, opposite the projection m, are notched to fit the shank or vertical portion thereof, and permit the said flanges to come in contact, or nearly so, with each other.

The two **I**-portions of the beam are now securely fastened together by bolts n, connecting the two webs p, which renders the attachment to the chord complete.

The projection m may be cast with a flange at the top, to overlap the flanges of the beam, as represented, although this is not essential, as the weight of the beam and floor are sufficient to prevent vertical movement.

This connection of the beam to the chord is of the most simple character, yet it effectually accomplishes the required purpose of securing the beam in place, whereby it is made to perform the two additional functions of tie and roller-beam before specified, the importance of which is obvious.

What I claim as my invention, and desire to secure by Letters Patent, is—

1. The cast-iron chord-connection A, constructed with vertical longitudinal partitions g, and bosses h and h', substantially as herein described.

2. The projection m of the block A, arranged with the "two **I**" beam D, as herein described.

CHAS. KELLOGG.
